UNITED STATES PATENT OFFICE.

CALEB H. BRADLEY, OF WEST CHESTER, PENNSYLVANIA.

RAILWAY-CAR.

SPECIFICATION forming part of Letters Patent No. 256,631, dated April 18, 1882.

Application filed February 21, 1882. (No model.)

To all whom it may concern:

Be it known that I, CALEB H. BRADLEY, a citizen of the United States, resident at West Chester, in the county of Chester and State of

5 Pennsylvania, have invented a new and valuable Improvement in Railroad-Cars; and I do hereby declare that the following is a full, clear, and exact description of the construction and operation of the same, reference being had 10 to the annexed drawings, making a part of this specification, and to the letters and figures of reference marked thereon.

Figure 1 is a cross-sectional view of a portion of the top of a car-body, showing my improvement, and Fig. 2 is a longitudinal sectional view of the same.

This invention has relation to railway-cars; and it consists in the construction and novel arrangement in the top of a car of an opening 20 or openings of sufficient size to permit the passage of a person, and in connection therewith of a cover or covers and fastenings therefor adapted to be operated from the inside or outside of the car, all as hereinafter set forth, and 25 particularly pointed out in the claim.

In the accompanying drawings, the letter A designates the top or roof of an ordinary passenger-car, having the supporting rafters or transverse beams B. An opening is made in 30 the top or roof, between the ribs or rafters, so that the roof shall not be weakened thereby. The marginal boards d of the opening are designed to be raised a few inches above the roof to prevent water from entering. The raised 35 margin d is designed to be covered with water-proof material, which should be carefully connected to the water-proof covering of the roof.

E represents the cover, which is made with

a flange, F, extending downward around the raised margin d of the opening, and the cover 40 is designed to be covered with water-proof material.

In order to secure the cover or lid E in position so that it cannot be blown off, a fastening is employed which can be operated from 45 either the outside or the interior of the car. In the drawings, e represents a pin, stop, or catch, secured to the inside wall of the margin of the opening; and G indicates a rotary hook extending through the cover or lid, which is 50 provided with a suitable bearing therefor. Above the lid the handle g of the hook projects, so that it can be readily turned from the outside. Its engaging end being in full view on the inside of the car, it can also be easily 55 operated by the occupants should occasion require.

One end of the cover may be hinged to the marginal frame of the opening, if desirable; or the cover may be secured by fastenings of 60 the character mentioned at both ends.

Having described this invention, what I claim, and desire to secure by Letters Patent, is—

In a car-roof, the man-opening C, having the 65 raised margin d, the flanged cover E, the catches e, and the hooks G, having handles g projecting above the roof, substantially as specified.

In testimony that I claim the above I have 70 hereunto subscribed my name in the presence of two witnesses.

CALEB H. BRADLEY.
